FOOTWEAR SOLE

William Gottlieb, Davenport, Iowa, assignor to The Servus Rubber Company, Rock Island, Ill., a corporation of Illinois

Filed Sept. 13, 1966, Ser. No. 3,847

Term of patent 14 years

(Cl. D2—320)

I claim:

The ornamental design for a footwear sole, substantially as shown.
